The ornamental design for a combined printer and scanner, as shown and described.

DESCRIPTION

FIG. 1 is a perspective view of a combined printer and scanner;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a perspective view thereof with its handle in an alternative position.

The broken lines are for illustrative purpose only and form no part of the claimed design.
